FOUNTAIN BRUSH

Hazen George Lomas, Detroit, Mich.

Application May 25, 1934, Serial No. 727,539

1 Claim. (Cl. 15—136)

The present invention relates to a fountain brush especially adapted for shaving purposes.

One of the objects of the present invention is to provide a brush of this character, which will eliminate the use of the tube of cream now generally used for shaving purposes.

A still further important object of the invention is to provide a fountain brush which is cheap to manufacture, clean, sanitary and economical to use.

A still very important object of the invention is to provide means for regulating the flow of cream or fluid from the bulb and means for distributing the fluid throughout the hair of the brush.

Another important object of the invention will be found to reside in the means provided for preventing the flow of fluid from the brush, to the end that the brush may be packed away in a suitcase, trunk or the like, for traveling purposes.

In the accompanying drawing, forming a part of this application, wherein like numerals designate corresponding parts throughout the same,

Figure 1 is a front elevational view partly in section of the fountain brush, showing it in its assembled position,

Figure 2 is a horizontal sectional view of Figure 1, taken on line 2—2 thereof, looking in the direction of the arrows,

Figure 3 is a front elevational view of the fountain brush, showing the bulb removed from the brush head, and

Figure 4 is a vertical sectional view of the soap feeding mechanism.

In the accompanying drawing, wherein for the purpose of illustration, there is shown a preferred embodiment of the invention, the numeral 6 generally designates the brush head which is of cylindrical shape, having a central bore, the lower end being bent inwardly as clearly illustrated in Figure 1, and the inner upper portion being internally threaded. Within the brush head 6 there is secured a disk 8 having a centrally disposed bore therein, through which there

extends the feed pipe 9. As clearly illustrated in Figure 1, the central portion of the disk 8 is provided on its upper surface with a cone-shaped projection, the inner sides of which closely embrace the feeding tube 9, which is welded thereto.

The disk 8 is centrally located and secured in the bore of the brush head 6, dividing the brush head into a lower bristle receiving portion 7, in which there is firmly secured in the usual manner, the hair or shaving bristles 12. The feed pipe 9 projects above the disk 8 and extends be-

low the disk, to substantially the central portion of the bristle 12.

It is to be further noted in this connection that the hair bristles 12 completely fill the lower cavity of the brush head and snugly embrace and surround the outer surface of the feed pipe 9. To the lower portion of the feed pipe 9 there is secured a rubber tubing 14 which terminates short, as illustrated in Figure 1 of the lower ends of the hair bristles 12 and the lower free end of 10 the tubing 14 is serrated or toothed for a purpose to be more fully hereinafter described.

In the feed pipe 9 directly above the apex of the projecting portion of the disk 8 there is provided oppositely disposed inlet ports or apertures 16. The upper portion of the feed pipe 9 is internally threaded into which there is adapted to be screwed a thumb screw or valve 18 which may be regulated with respect to the inlet ports 16, to the end that the flow of liquid may be controlled, 20 or if so desired, completely stopped.

In the upper portion of the brush head 6 there is internally threaded a bulb supporting collar 20 having a centrally disposed bore therein which communicates with the inner upper portion of 25 the brush head defining a soap well, 21.

As clearly illustrated in Figure 1, the lower portion of the bulb 22 fits over the circular upper portion of the collar 20, closely embracing the same and securing the bulb thereto. The upper 30 portion of the rubber bulb is of substantially frusto-conical shape and is constructed of such a size, as to adequately accommodate a supply of fluid, such as soap to last over a reasonable period of time.

On the outer surface of the bulb there is provided integral, spaced, longitudinally disposed ribs 24 providing a gripping surface to facilitate the squeezing and unscrewing of the bulb. It is also to be noted that the upper portion of the 40 bulb 22 is substantially flat to the end that the same whether filled with soap or empty, can be positioned in an upright position.

The thumb screw valve 18 may be adjusted to any desired position relative to the inlet ports 45 to regulate the flow of soap through the inlet port 16 into the feed pipe 9 and consequently to the brush hairs 12. It is noted in this connection that when it is desired to place the fountain brush in a trunk, suitcase, or the like, in traveling, the thumb screw valve 18 may be moved to its lowermost position, closing the inlet ports 16 and thereby preventing the flow of fluid through the feed pipe 9.

The depending tubing 14 secured to the feed 55

pipe 8 is constructed of a soft rubber material and the free end thereof which terminates short of the ends of the brush hairs, is serrated or toothed, to present a sharp, soft pointed surface of substantially the same character as the brush hairs, to the end that a pleasing effect to the face is obtained. This rubber tubing secured to the feed pipe or tube, is considered one of the salient features of the invention, in that it terminates just short of the free end of the brush head, thereby permitting of a distribution of the soap in that portion of the brush hair which contacts the surface of the user.

While there is shown for the purpose of illustration a preferred embodiment of the invention, it is to be specifically understood that it is capable of various changes and modifications, without departing from the spirit thereof, and it is intended therefore, that only such limitations shall be imposed thereon as are indicated in the prior art or the appended claim.

Having thus described the invention, what is claimed is:

A brush of the class described, comprising a head having a centrally arranged passageway therethrough and an internally threaded upper portion, a transversely disposed disk in said passage dividing said head into an upper fluid well and a lower bristle receiving portion, said disk having an upwardly extending integral frusto-conical shaped central portion with a longitudinally extending bore therein, bristles secured in said lower portion, a longitudinally disposed feed pipe in said bore in said disk projecting into the fluid well and extending into the bristles, said portion of said feed pipe in the fluid well being provided with fluid inlet ports adjacent the upper portion of the frusto-conical-shaped portion, a tubing of soft rubber material secured to the lower end of said feed pipe and terminating short of the lowermost end of said bristles, said feed pipe on the free end thereof being serrated, an adjustable valve for said ports, and a frusto-conical shaped fluid receiving bulb secured to the upper portion of said brush head.

HAZEN GEORGE LOMAS.
